UNITED STATES PATENT OFFICE.

JAMES P. BURKE, OF STRUTHERS, OHIO.

SAFETY PUSH-PIN.

1,303,025.

Specification of Letters Patent.

Patented May 6, 1919.

Application filed April 16, 1918. Serial No. 228,900.

To all whom it may concern:

Be it known that I, JAMES P. BURKE, a citizen of the United States, and a resident of Struthers, in the county of Mahoning and 5 State of Ohio, have invented a new and Improved Safety Push-Pin, of which the following is a full, clear, and exact description.

This invention relates to fasteners in the nature of pins, tacks, or the like that are 10 commonly used for the purpose of attaching small pictures, calendars, advertising matter, printed sheets, cards or the like to relatively fixed objects such as walls, railings, window frames or the like. By the term 15 "card" as used hereinafter I wish therefore to be understood as meaning to cover any relatively light object adapted to be fastened or supported by my improved device.

Among the objects of the invention is to 20 provide a pin so designed for supporting a card in the manner indicated as to insure not only reliable service in such support, but particularly to insure the utmost safety to the operator's fingers either before, during, 25 or after the device is operated for its purpose.

More specifically stated I provide a push pin having a necessary point for projection into the supporting object, but so constructed 30 as to provide automatically a guard to prevent the point of the pin under normal conditions from pricking the operator's fingers or scratching or otherwise abrading either the operator's person or his clothing or any 35 other device.

With the foregoing and other objects in view the invention consists in the arrangement and combination of parts hereinafter described and claimed, and while the invention 40 is not restricted to the exact details of construction disclosed or suggested herein, still for the purpose of illustrating a practical embodiment thereof reference is had to the accompanying drawings, in which like 45 reference characters designate the same parts in the several views, and in which

Figure 1 is a front elevation showing my device in holding position.

Fig. 2 is a vertical section on the line 50 2-2 of Fig. 1.

Fig. 3 is a view on the same plane as that of Fig. 2, but indicating the normal position of the safety push pin with respect to the card prior to the projection of the point 55 through the card and into the wall or other support.

Fig. 4 is a plan view of the blank but with the point stamped therefrom prior to its formation into the preferred final form.

Fig. 5 is a horizontal sectional detail on 60 the line 5-5 of Fig. 2.

Fig. 6 is a similar view on the line 6-6.

Fig. 7 is a detail perspective view indicating a modified form of the push pin.

Figs. 8 and 9 are detail perspective views 65 indicating different means for attaching the base portion of the pin to a card.

Fig. 10 is a side elevation indicating the form of invention in Fig. 9 applied to the card, the card being in section; and 70

Fig. 11 indicates one of the many different modified forms that may be assumed by the point of the pin.

Referring now more particularly to the first set of figures I show a push pin formed 75 preferably of relatively thin resilient or spring metal comprising a body 15 having side edges of any desired relation to each other preferably parallel and provided at or adjacent to its upper end with an integral 80 point 16. The lower end of the body is bent into a loop 17 which in the present instance after passing through a slot 18 formed in a card 19 may be gripped to the card adjacent to the slot by the projection of teeth 20 or 85 the like directly into the card. As will be noted especially in Fig. 3 the formation of the body is such as to provide at or about the point 21 a fulcrum which by virtue of the gripping of the loop portion of the body 90 upon the card preserves a definite or fixed relation to the card while the remaining or upper portion of the body has an inherent tendency due to the resiliency of the body to bear a spaced relation to the card, the upper 95 end of the body being spaced thereby from the card a distance equal to about the length of the point portion 16. It will thus be appreciated that with the device as a whole attached to a card as indicated in Fig. 3 the 100 sharp point is so guarded as to protect the operator from danger of being injured thereby while the card with pin attached is being handled.

To support the card, however, upon the wall 22 or other supporting means 105 the operator will push upon the smooth side of the body with his thumb and thereby cause the point to pass directly through the card and into the wall where it will be held by friction. I wish to observe at this time also 110 that by the making of the device of metal that is sufficiently flexible the push pin may

be used to good advantage for attaching tickets to dry goods or other analogous merchandise. For this purpose the merchandise may be introduced between the body of the 5 pin and the ticket and the point bent over directly upon the ticket or the operation may be performed as indicated in Fig. 2 and the point bent over upon the opposite side of the fabric from the ticket. The printed matter 10 or markings upon the ticket obviously may be arranged on either side as may be deemed best.

Since the device is made preferably of 15 relatively thin metal the point 16 which is made directly therefrom requires ordinarily a certain amount of reinforcement to provide the desired rigidity especially in the operation of the device in connection with a hard wood support for example. I, therefore, prefer to strike out of the body of the 20 pin sufficient stock to form the body of the point of considerable width, and then by suitable dies roll this point body into the form of a hollow cone as indicated best in 25 Figs. 5 and 11. It, therefore, has ample strength for every purpose and yet the sharp portion of the point is sufficiently slender for penetration and bending purposes. As 30 already indicated the point may be struck out from within the body but as indicated in Fig. 11 it may be formed at the extreme end of the body 15', the point 16' being bent downward instead of upward into right 35 angular position with respect to the main portion of the body.

In Fig. 7 the body 15, point 16 and loop 17 are indicated as being substantially the same in form as in the first set of figures and providing in connection with the card the same 40 fulcrum expedient 21. Instead of the grip between the pin and the card being accomplished by means of the teeth 20 or other means engaging into the card I may provide a flat guard member 23 extending up 45 from the slot 18 to a point on a level with or above the top of the body. This guard member is provided with a hole or slot 24 registering with the point 16 and so arranged that such point while guarded normally 50 in the open position of the pin by the upper end of the guard will permit the point to be projected directly through the slot and thence into the wall in practically the same manner as indicated in Fig. 2, although the 55 card may be suspended below the point of attachment of the point 16 so as to provide for attachment of the pin through a relatively narrow margin of the card. Obviously the manner of formation of the point

16' indicated in Fig. 11 may be embodied 60 in the metal guard structure shown in Fig. 7 in which case the guard member will project somewhat above the point or body structure. Figs. 8, 9 and 10 show various ways 65 in which the base portion of the body may be fastened to good advantage to the card. In Fig. 8 the body 15^a is provided with two 70 prongs 25 and 26 both struck from the same portion of the metal or more accurately with the tongue 25 struck out of the tongue 26 while the latter may constitute portion of the flat structure in its original form. These 75 tongues, however, are bent from about the same horizontal line and in opposite directions after being projected through the card and so clenched down upon the side of the card opposite from the body 15^a. The width of the tongue 26, however, provides that fulcrum shoulders 21' are observed which as 80 in the other forms of the invention serve to hold the main portion of the body spaced from the card or other guard means for the purposes already set forth. In Figs. 9 and 10 the tongue 25' is struck out from between the two tongues 26' after these parts are 85 passed through the slot 18 of the card 19, the fulcrum shoulders 21' being observed as before indicated. Fig. 9 indicates that form of the device in which the body 15^b is narrower than other parts of the device for the 90 purpose of conserving weight and material.

I claim:

1. In a safety push pin, the combination of a thin sheet metal body and a puncturing pin formed as an integral part of the body, 95 the structure of the pin being formed from a relatively wide portion of the body and formed into a conical roll to provide a stiffening reinforcement for the pin.
2. In a safety push pin, the combination 100 of a sheet metal body of relatively thin resilient nature, means at one end of the body to fix the same to a card with the adjacent end portion of the body lying flat against the card, the normal position of the remainder of the body being deflected away from the plane of the card while the portion lying flat against the card constitutes a fulcrum, and a point structure formed adjacent to the opposite end of the body and 105 bent at an angle thereto and normally spanning the space between the adjacent end of the body and the plane of the card, the body being bendable around said fulcrum point in the projection of the point across the 110 plane of the card into a rigid support.

JAMES P. BURKE.
